UNITED STATES PATENT OFFICE.

WILLIAM L. BEALL, OF ALBION, MICHIGAN, ASSIGNOR TO THE GALE MANUFACTURING COMPANY, OF SAME PLACE.

DESIGN FOR A CULTIVATOR-FRAME.

SPECIFICATION forming part of Design No. 30,680, dated May 2, 1899.

Application filed April 4, 1899. Serial No. 711,743. Term of patent 7 years.

To all whom it may concern:

Be it known that I, WILLIAM L. BEALL, a citizen of the United States, residing at Albion, in the county of Calhoun and State of Michigan, have invented and produced a new and original Design for a Cultivator-Frame; and I do hereby declare the following to be a full, clear, and exact description of the same, reference being had to the accompanying drawing, forming a part thereof.

My invention consists in a novel design for a cultivator-frame, and in the accompanying drawing I have illustrated my design.

The design consists of the parallel bars A A, the inner angular bar B having a portion b parallel to the bars A A and portions b' b' connecting the portion b with said bars A A, said portions b' b' inclining toward each other,

as shown, and the outer bars C C having portions extending from the bars A A, parallel to the portions b' b' of the bar B, to their junction with the portion b, and then inclining toward each other sharply, as shown at c c.

Minor features of my design are the inclined bars D D, extending from the bars C C to the outer ends of bars A A.

What I claim, and desire to secure by Letters Patent, is—

The design for a cultivator-frame, substantially as herein shown and described.

In testimony whereof I affix my signature in presence of two witnesses.

WILLIAM L. BEALL.
